UNITED STATES PATENT OFFICE.

FLOYD C. WEAVER, OF WASHINGTON, DISTRICT OF COLUMBIA.

PROCESS FOR LAPPLNG GAUGE BLOCKS.

Original application filed January 17, 1922, Serial No. 530,007. Patent No. 1,476,863, dated December 11, 1923. Divided and this application filed September 6, 1922, Serial No. 586,521.

To all whom it may concern:

Be it known that I, FLOYD C. WEAVER, a citizen of the United States, residing at Washington, District of Columbia, have invented certain new and useful Improvements in Processes for Lapping Gauge Blocks, of which the following is a specification, reference being had therein to the accompanying drawings.

This invention relates to a process for making precision true plane surfaces, and the object of the invention is the production of precision true planes or true plane surfaces, and also of precision true plane surfaces precisely parallel to each other and at a given or designated separation from each other for any desirable or practical material, such as glass, metal, natural crystals, et cetera, the surfaces to be plane and parallel to optical interference testing accuracy.

This application is a divisional case, of my application, filed January 17, 1922, Serial No. 530,007, upon which U. S. Patent No. 1,476,863 issued on December 11, 1923.

With the foregoing and other objects in view, my invention comprises certain novel combinations, constructions and arrangements of parts as will be hereinafter described, illustrated in the accompanying drawings, and more particularly pointed out in the appended claim.

In the drawings:

Figure 1 is a fragmentary, transverse, sectional view through one form of a lapping machine used in rough lapping processes.

Figure 2 is a fragmentary, transverse, sectional view through the machine partly illustrated in Fig. 1, with certain mechanical parts removed to permit the device to accommodate the final lapping process.

Figure 3 is a transverse, sectional view of the machine as employed for the purpose of lapping spheres.

Figure 4 is a fragmentary plan view of a part of the lapping machine, illustrating the manner in which cylinders are mounted upon the device when they are to be lapped.

Figure 5 is a fragmentary plan view of the device illustrated in Fig. 3.

Inasmuch as my machines for performing the processes are fully described in my U. S. application, Serial No. 530,007, filed Jan-

uary 17, 1922, upon which U. S. Patent No. 1,476,863 issued reference can be had to said patent, as it is only necessary to describe the specific process in this case. The precision lapping and the optical polishing of plane and plane parallel surfaces of gauge blocks or of end standards, et cetera, is accomplished by three distinct process operations, following a precision mechanical to 0.0002" over nominal size of the gauge blocks, et cetera.

The first sizing operation is done on the equipment shown in Fig. 1, where the gauge blocks 10 are mounted in perforations of the thin plate 14 operated by the driving or stroke pin 13, and moved between the two independent plates 11 and 1. The master plate 1 is mounted upon the work carrying plate 2 and is rotated automatically or at the will of the operator, while the lapping plate 11 is lowered by the progress of the lapping of the ends of the gauge blocks 10 until the carrying ring plate 18 rests upon the limiting or stop ring 17, which is previously adjusted for a fixed height or length of the secondary standard or gauge block 16 or some desired final length or height of the gauge blocks 10. Thus the lapping proceeds until the lapping plate 11, which is rigidly attached to the carrying ring plate 18 by means of ring 19, comes to the limiting position denoted by the position of the stop ring 17. Upon completion of the lapping, the lapping plate 11 is lifted off together with the thin plate 14, after the driving or stroke pin 13 is removed, thus leaving the gauge blocks 10 then rough sized to 0.00005" on top of the master plate 1, which are then taken off and cleaned for inspection and preliminary measurements.

The second or precision lapping operation is done on the machine shown in Fig. 2. The gauge blocks 10, after sizing operation, are carefully set in intimate contact on the master plate 1, i. e., by wringing, and the spaces between the gauge blocks and the metal ring 24 are filled with hard wax or resin 24^a nearly to the level of the top edge of the ring 24 and then the exposed surface is proof coated to resist action of liquids carrying the lapping abrasives, such as lime water, gasoline and oils, benzols, et cetera. After this wax or resin 24^a has hardened wedges 35^a are carefully placed at symmet-

rical intervals, thus securing the ring 24 and the gauge blocks 10 in the bed of wax or resin to the auxiliary ring 3, preventing displacement of the gauge blocks during the lapping process. Precaution is to be taken to insure the cleanliness of the lapping surface of the lapping plate 11 before putting the plate in position on top of the gauge blocks 10. With the lapping plate 11 thus in place and the stop ring 17 set for the proper value according to the secondary standard or gauge block 16, with the allowance set by the graduated nuts 22 and which are secured by the nuts 21, clearly shown in my hereinbefore mentioned Patent No. 1,476,863, the pin 13 is connected and the lapping operation is started. As the lapping plate 11 is given a stroking motion by the pin 13, which is connected to suitable power sources, the master plate 1 fastened to either automatically or at the will of the operator. Thus the top faces of the gauge blocks 10 are reduced by the lapping effort of the plate 11 until the carrying ring plate 26 (see my prior Patent No. 1,476,863) engages the stop ring 17, when the operation is completed. The stop ring 17 is set for the first surface to lap off approximately 0.000020" of the excess stock left by the first sizing operation, i. e., 0.000050". Thus there is left approximately 0.000030" for the second part of the precision lapping operation.

The second part of the precision lapping operation consists in removing the lapping plate 11 with the carrying ring plate 26 and the ring 19, as well as the stop ring 17 and the sleeves 8 and the studs 20 and nuts 21 and 22 of said patent. After the wedges 35^a are removed, the metal ring 24 is given a sharp rap with a hammer on the end of a soft wood block held tightly against the edge in a parallel plane to the surface of the master plate 1. This sharp blow causes no harm and is enough to start the ring 24 and the mass of wax or resin and gauge blocks 10 loose from the surface of the master plate 1. In cases where all the gauge blocks 10 do not come off readily the wax or resin is dissolved or chipped off and the gauge blocks, slightly warmed, are then removed one at a time. Care is necessary at all times to preserve the surface of the master plate 1 from any injury, as its surface is kept in perfect condition as the primary reference surface, both of this process operation and the succeeding ones.

After removal of the gauge blocks 10, with all parts, and the surface of master plate 1 is thoroughly cleaned, the gauge blocks are reset with this last precision lapped surface down on the master plate 1, in the same manner as above described for the first precision lapped surface. The lapping then proceeds in the same way after re-

placing the stop ring 17 and the other rings associated therewith, the lapping plate 11 and the pin 13 in position as for the first surface, and graduated nuts 22 (see my Patent No. 1,476,863) are set for the final tolerance or excess stock amount, i. e., which should be approximately 0.00002". That is, this last operation of the precision operation should take approximately 0.00001" from the previously remaining 0.00003" and thus leaving the 0.00002" for the following final operation. The gauge blocks 10 are again removed as before and are cleaned for inspections and tests. Thus the gauge blocks are ready for the final perfecting lapping and optical polishing stage.

The perfecting lapping and the optical polishing process is done on the machine shown in Fig. 2, where the gauge blocks 10, lapped in the preceding process to within 0.000020" over size, are now carefully set or wrung on the master plate 1. The stop ring 17, the studs 20, the nuts 21 and 22, the sleeves 8, (see my Patent No. 1,476,863) the carrying ring plate 18 and the ring 19 are all removed, leaving the lapping plate 11 free for stroking by the pin 13 over the top surfaces of the gauge blocks 10 for either the lapping or polishing. In the final lapping a suitable abrasive medium is fed through the vents 23 in the lapping plate 11 to the gauge blocks 10. The lapping in this precision stage is again only on one surface at one time. This first lapping stage is intended for the removal of approximately 0.000010", with very frequent tests by optical flat and standard gauge set on the extending portion of the master plate 1 beyond the ring 24, thus readily and precisely following the dimensional progress of the work.

Following this lapping operation where the highest finish is secured the optical polishing is proceeded with in a similar manner. The lapping plate 11 is coated on the lapping surface with a polishing pad of wax or pitch made flat against a plane master surface while still plastic from heating and then allowed to cool. This surface is then cut by grooves making a checked pattern as is done for the metal lapping plate 11 and vents 23. In operation the plate 11 with its polishing pad and polishing compound are worked by stroke pin over the top surfaces of the gauge blocks 10 in precisely the same manner as for the lapping operations. The master plate 1 on the carrying plate 2 is either rotated automatically or at the will of the operator. Upon completion of this top surface of the gauge blocks 10 with an optical polish and answering the interference tests for flatness the gauge blocks 10 are then removed as heretofore described and then reset upon plate 11 with the polished surface wrung on the top surface of

the master plate 1. With the setting of band 24 et cetera and the wedges 35 the lapping of the last face of the gauge blocks 10 is begun. The gauge blocks 10 at this stage have approximately 0.000010" to be removed. The lapping plate 11 is first given a series of symmetrical stroking movements by pin 13 and then the gauge blocks are carefully tested after removing the lapping plate 11 by an optical master flat surface and a standard gauge set upon the extending portion of the master plate 1 within the ring 24. Thus the exact dimensional or length chart is made of the gauge blocks 10, showing which portion of the whole is the highest and where greater lapping is necessary to bring all the gauge blocks 10 to precisely the same length. In case of a section of the gauge blocks 10 having a greater length the center of the lapping plate 11 is shifted to have a series of short circular or elliptical strokes over the particular high portions, which is accomplished by operating master plate 1 to bring these high portions at will to a point of maximum lapping effort. Thus by following each measured period of lapping effort of the lapping plate 11 by testing with an optical master surface and the standard gauge as above described gauge blocks 10 can be brought down step by step to the final value, which in practice means this last lapping and correcting should be carried approximately to within 0.00003" of final size.

With the completion of this perfecting stage of lapping, the gauge blocks 10 are now given an optical polish as above described for the first surface. During the progress of the polishing frequent tests with the optical master surface and standard gauge will prevent in some cases excessive polishing and the reduction of the remaining stock or more than the 0.00003". Generally this polishing can be carried to within 0.00002" or less for final size, leaving the gauge blocks 10 optically polished, optically plane surfaced, optically plane parallel faced, and precisely the given length to within 0.00002" or less over nominal value, without any marring of a previously given finish to the now lapped faces or surfaces. Both glass and metal blocks 10 are worked in similar ways. The original setting of the blocks 10 is slightly different when the master plate 1 is made of glass and when the gauge blocks 10 are glass and the resin between the gauge blocks 1 is replaced with plaster Paris or compounds which are principally calcium carbonate.

The process for lapping precision spheres and precision cylinders is done upon the equipments or machines shown in Figs. 2 and 3. The arrangements of the spheres 35, as shown in Figs. 3 and 5, with the sys-

tem of movable concentric bands 29 are placed upon the master plate 1 within the band 28, which is secured by wedges 35, as shown in Fig. 3, and the lapping plate 11 is operated in precisely the same manner as above described for the gauge blocks in Figs. 1, 2 and 3. The lapping plate 11 is stroked by pin 13 and the master plate 1 is rotated either automatically or at will of the operator. The first stages of lapping are accomplished on the machine shown in Fig. 3, with the lapping plate 11 secured to the carrying ring plate 26 by means of the ring 19, thus the lapping may be continued until the ring plate 26 (see my prior Patent No. 1,476,863) comes into contact with the stop ring 17 set for the secondary standard or gauge block 16 which in turn determines the size of the spheres 35. After completion of this first stage of the lapping plate 11 can be removed and prepared for the final perfecting lapping as shown in Fig. 2, where all the operating processes for the gauge blocks 10 are repeated for the spheres 35 mounted as shown in Figs. 4 and 6. The diameters of the spheres 35 are directly measured by an optical master surface and a standard gauge, as before described for the gauge blocks 10. Thus the size of the spheres is controlled as readily as in the case of the gauge blocks 10, due to the principle of the two successive concentric ring bands 29 binding the spheres 35 at two points in addition to the point of contact of the spheres with the master plate 1, giving a vice grip upon the spheres as the lapping plate 11 is driven over the top contact of the spheres. The action of the lapping plate 11 bearing on the spheres 35 in the direction of the movement of the lapping plate 11 or the relative movement of the lapping plate 11 to the master plate 1. The concentric ring bands 29 prevent or resist individual movement of the spheres 35, and the resulting composite effect of the rolling spheres is a crowding of the ring bands together at points where the motion of the lapping plate 11 is in the direction of a radius of the bands, thus clamping the spheres between two successive bands and the lapping plate 11 removing the high projecting portions of the spheres. The stroke pin 13 is given a series of symmetrical strokes to give a maximum lapping effort in a variety of directions closely approximately the radii of the bands 29. In lapping spheres 35 by the machine shown in Fig. 3, the diameters of such spheres can be brought to within 0.000100" of desired size readily and in the final lapping as shown in the machine illustrated in Fig. 4, the diameters of the spheres can be brought to the limit of 0.000050".

In the process of lapping precision cylinders, the machine shown in Fig. 4 is used

as above described for spheres throughout, excepting that the pin 13 is given a principal direction normal to the axis of the cylinders 30 or at a varying small angle to a normal direction. The parallel sided and hardened bars 34 fitting loosely in notches in the bars 32 perform the same function as the bands 29 in the case of the spheres 35. In operation the annular ring 31 in Fig. 5 and the bars 32 are placed upon the master plate 1 and then the limiting outer band 28 is secured by wedges 35, the same as they retain the metal band 24 in Fig. 2, and the rectangular bars 34 are dropped into their respective notches in the bars 32. The cylinders 36 previously machine ground to within 0.00005" of diameter are dropped in the pockets between successive bars 34 and bearing on the surface of the master plate 1. The top lapping plate 11 of Fig. 3, with its ring plate 26 and the ring 19, is then put in place with the lapping surface of the plate 11 resting on the upper portions of the cylinders 30 and the stop ring 17 adjusted to the secondary standard or gauge block 16 and the lapping operation is then proceeded with in the manner

hereinbefore set forth for the gauge blocks 10.

What I claim is:

A process of the character described comprising placing articles to be ground upon a support having a flat upper article receiving face with the articles held in spaced relation to each other and grinding the upper ends of the articles a predetermined amount to provide end faces parallel to the article engaging face of the support, then inverting the articles and placing a waterproofed plastic about and between the articles to hold the articles in place, then grinding the previously unground ends of the articles to remove a predetermined amount of material and provide end faces parallel to the previously ground end faces, removing the articles and plastic from the support and thoroughly cleansing the articles and subjecting the end faces thereof to a final grinding to reduce the articles to a desired size with their end faces exactly flat and parallel to each other.

In testimony whereof I hereunto affix my signature.

FLOYD C. WEAVER.
